CLAIM

The ornamental design for an endoscope mouthpiece and drape in combination, as shown and described.

DESCRIPTION

FIG. 1 is a top, rear and right side perspective view of an endoscope mouthpiece and drape in combination showing my new design;

FIG. 2 is a front elevational view thereof;

FIG. 3 is a rear elevational view thereof;

FIG. 4 is a top plan view thereof;

FIG. 5 is a left side elevational view thereof;

FIG. 6 is an enlarged view of the region indicated in FIG. 1;

FIG. 7 is an enlarged view of the region indicated in FIG. 2;

FIG. 8 is an enlarged view of the region indicated in FIG. 3;

FIG. 9 is an enlarged view of the region indicated in FIG. 4;

FIG. 10 is an enlarged view of the region indicated in FIG. 5;

FIG. 11 is a top, front and right side perspective view thereof, showing the drape in a folded configuration;

FIG. 12 is a front elevational view thereof;

FIG. 13 is a rear elevational view thereof;

FIG. 14 is a top plan view thereof;

FIG. 15 is a left side elevational view thereof;

FIG. 16 is a cross-sectional view thereof taken along line XVI-XVI of FIG. 7;

FIG. 17 is a cross-sectional view thereof taken along line XVII-XVII of FIG. 7;

FIG. 18 is a top, front and right side exploded perspective view of the area indicated in the enlargements;

FIG. 19 is a top, front and right side perspective view thereof, shown in its environment of use; and,

FIG. 20 is a top, front and right side perspective view thereof, shown with the drape in a folded configuration and with adhesive tape attached.

The long-dash short-dash broken lines in FIGS. 6-10 and 18 represent the bounds of the enlargements taken from FIGS. 1-5 and form no part of the claimed design. The dash-dash
